UNITED STATES PATENT OFFICE.

HENRY M. KEITH, OF WEST FRANKFORT, ILLINOIS.

PUMP.

1,411,173.

Specification of Letters Patent. Patented Mar. 28, 1922.

Application filed July 10, 1920. Serial No. 395,250.

To all whom it may concern:

Be it known that I, HENRY M. KEITH, a citizen of the United States, residing at West Frankfort, in the county of Franklin 5 and State of Illinois, have invented new and useful Improvements in Pumps, of which the following is a specification.

This invention relates to rotary pumps, and has for its chief characteristic the provision of means carried by the drive shaft, 10 and operable to increase the force of the water supply.

To this end, the invention makes use of a rotor disposed within the pump casing, and 15 including a pivoted section which is effectively maintained in contact with the wall of the casing to forcibly drive the water from the casing through the outlet of the pump.

Another object of the invention resides in 20 the provision of a pump of the above mentioned character, wherein more than one rotor may be employed, the pump having a single inlet and outlet for all of the rotors, 25 and the construction and arrangement of parts is such that leakage is prevented and the efficiency of the pump increased.

The nature and advantages of the invention 30 will be better understood when the following detail description is read in connection with the accompanying drawings, the invention residing in the construction, combination and arrangement of parts as claimed.

In the drawings forming part of this application like numerals of reference indicate similar parts in the several views and 35 wherein—

Figure 1 is an elevation of the pump with 40 one of the side plates removed.

Figure 2 is a vertical sectional view therethrough taken at right angles to Figure 1.

Figure 3 is a view on an enlarged scale 45 similar to Figure 2 of a duplex construction.

Referring to the drawings in detail, and particularly to Figures 1 and 2, 10 indicates the pump casing of the desired construction, one side 11 of the casing being removable as shown. A drive shaft 12 is rotatably mounted in bearings 13 and supports the rotor 14 within the casing 10. The rotor is of substantially cup-shaped formation in cross section, the opened end of 50 which is closed by means of the side mem-

ber 11 of the casing. The shaft 12 may be driven in any suitable manner and is equipped with a gear 15 for this purpose. A rotor is equipped with a packing ring 16 which bears against the member 11 of the 60 casing as shown. The rotor includes a pivoted section 14' which is pivoted as at 17 and designed to provide a broad surface for increasing the force of the water supply. The hinged section 14' is permanently held 65 in contact with the wall of the casing 10. Secured to the member 11 of the casing is an eccentric 19 having a bore for the reception of the drive shaft 12, which is provided to cause the pivoted or hinged section 14' of the rotor to travel in a true 70 course around the wall of the casing 10. Interposed between the hinged section 14' of the rotor and the eccentric 19 is a roller 20 which moves over the periphery of the eccentric 19, a spring 21 being utilized to compensate for wear, and hold the hinged section 14' in effective engagement with the wall of the casing 10. The inlet of the 75 pump is indicated at 22 and the outlet at 23, while interposed between said inlet and outlet is the packing 24 which bears against the periphery of the rotor 14. The packing is spring pressed, the spring being indicated at 25, while the tension of the spring 80 is regulated by means of an adjusting element 26. As herein shown, the pump is equipped with valves at 27 controlling communication between the casing 10 and the outlet 23 and the efficiency of the pump is 85 materially increased with the use of such valves when the pump is being operated at low speed. An air chamber is indicated at 90 28 arranged on top of the pump.

In Figure 3 I have illustrated a duplex 95 construction, wherein the pump casing is indicated at 30 and of a size to accommodate more than one rotor, there being two of these elements illustrated in the figure mentioned. The casing 30 is divided into rotor 100 chambers 31 by means of partitions 32 which are movable laterally but not rotatably. These partitions close the opened ends of the rotors 34 which are of the same construction as hereinabove described and 105 carried by the drive shaft 35. Between the partitions I have positioned an expandible element 36 by moving the partition laterally and holding the latter in effective engagement with the rotor to prevent leakage. 110

In the duplex construction there is but a single inlet and a single outlet for all of the rotors, while the spring pressed packing 37 is arranged to wipe the periphery of each rotor. The tension of these packing elements against the rotors is regulated by the adjusting element 38. The shaft 35 may be driven in any suitable manner and equipped with a gearing 39 for this purpose. The air chamber is indicated at 40.

In either of the constructions described, the water or fluid is admitted to the casing of the pump through the inlet thereof, and as the rotor is fixed upon the shaft for rotation therewith, this fluid is forced by the hinged section of the rotor to travel in the same direction as the rotor, and is forcibly discharged through the outlet port of the pump. The packing arranged between the respective ports, prevent the fluid from passing beyond the outlet port through the inlet port, thus allowing the intake side of the pump to form a vacuum and therefore allow the outside air pressure to force the water or other fluid into the intake chamber. By reason of the fact that the rotor is cup-shaped, the eccentric is positioned upon the same shaft as the rotor and arranged

within the latter providing for a very compact and efficient disposition of parts.

While it is believed that from the foregoing description the nature and advantages of the invention will be readily apparent, I desire to have it understood that I do not limit myself to the details herein shown and described, and that such changes may be resorted to when desired as fall within the scope of what is claimed.

What I claim is:

A device of the class described comprising a casing provided with an inlet port and an outlet port, a shaft journaled in suitable bearings in said casing, a cup-shaped rotor mounted on said shaft and having a pivoted section engaging said casing, a packing ring secured to said rotor and engaging said casing, an eccentric mounted on said shaft and secured to said casing, a coil spring carried by said hinged section, a roller interposed between said eccentric and said spring, and an adjustable spring influenced packing disposed between said ports and engaging said rotor.

In testimony whereof I affix my signature.

HENRY M. KEITH.
